UNITED STATES PATENT OFFICE

114,226

DESIGN FOR AN APPAREL PIN

Florence N. Lewis, New York, N. Y.

Application March 7, 1939, Serial No. 83,399

Term of patent 7 years

To all whom it may concern:

Be it known that I, Florence N. Lewis, a citizen of the United States, residing at New York, in the county of New York and State of New York, have invented a new, original, and ornamental Design for an Apparel Pin, of which the following is a specification, reference being had to the accompanying drawing, forming part thereof.

In the drawing:

Fig. 1 is a front view of an apparel pin showing my new design;

Fig. 2 is a top view thereof.

I claim:

The ornamental design for an apparel pin, as shown.

FLORENCE N. LEWIS.
